UNITED STATES PATENT OFFICE.

HANS RANSOM, OF CATTARAUGUS, NEW YORK, ASSIGNOR OF ONE-HALF
TO PETER LARSEN, OF SAME PLACE.

DESIGN FOR A HAMMER.

SPECIFICATION forming part of Design No. 33,330, dated October 9, 1900.

Application filed September 12, 1900. Serial No. 29,852. Term of patent 14 years.

To all whom it may concern:

Be it known that I, HANS RANSOM, a citizen of the United States, residing at Cattaraugus, in the county of Cattaraugus and State of New York, have invented and produced a new and useful Design for Hammers, of which the following is a specification.

My invention relates to new and useful designs in hammers, of which the following is a specification, reference being had to the accompanying drawings, forming a part thereof, and in which—

Figure 1 is a side elevation of my hammer. Fig. 2 is a front elevation of the same. Fig. 3 is a side elevation from opposite side.

Like numerals of reference designate like parts in the various views of the drawings.

As shown in the drawings, the numeral 1 designates the nose of my hammer, which is frusto-conical in contour and is formed integral with the eye 2. A skein is joined to the eye 2 and is formed of two straps 3, rounded off at 4 and concave at 5. The head of my hammer is curved up and back at 6,

and a V-shaped slot 7 traverses it throughout about one-half of its extent, thus forming two claws 8 and 9. The claw 9 is curved at 10, pointed at 11, and cut away at 12, making a square shoulder. The claws flare out and the base of the longer one is wider than the base of the shorter one.

The leading or material feature of my design consists of the conical nose 1, the convex skein or straps 3, and the unequal curved claws 8 and 9, the longer of which is pointed.

Having described my invention, what I claim as new, and wish to secure by Letters Patent, is—

The design for a hammer, as herein shown and described.

In testimony whereof I have hereunto set my hand in presence of two subscribing witnesses.

HANS RANSOM.
